UNITED STATES PATENT OFFICE.

JOHN M. SCOTT, OF RACINE, WISCONSIN.

RAIL-ANCHOR.

No. 814,627.

Specification of Letters Patent.

Patented March 6, 1906.

Original application filed March 10, 1904, Serial No. 197,477. Divided and this application filed December 22, 1905. Serial No. 292,985.

To all whom it may concern:

Be it known that I, JOHN M. SCOTT, a citizen of the United States, residing at Racine, in the county of Racine and State of Wisconsin, have invented certain new and useful Improvements in Rail-Anchors, of which the following is a specification, reference being had to the accompanying drawings, forming a part thereof.

10 The main objects of this invention are to prevent longitudinal movement or creeping of railway-rails upon the ties, to prevent the spreading of the rails, to insure against slipping of the rails in the anchor, and generally 15 to improve the construction and operation of devices of this class.

The invention consists in certain novel features of construction and in the peculiar arrangement and combinations of parts, as 20 hereinafter particularly described, and defined in the claims.

In the accompanying drawings like characters designate the same parts in the several figures.

25 Figure 1 is a vertical cross-section of a pair of railway-rails to which anchors embodying the present invention are applied, the anchor at the right being shown in elevation and the anchor at the left in section. Fig. 2 is a plan view and horizontal section of a pair of connected anchors as applied to railway-rails, the anchor at the left being shown in section. Fig. 3 is a side elevation of the anchor as applied to a rail and tie, the rail being shown in side elevation and the tie in cross-section; and Fig. 4 is an inside elevation of one of the 35 jaws.

a a designate a pair of parallel railway-rails, and *b* designates a tie to which they are 40 spiked or attached in the usual way.

The anchor constituting the present invention comprises a pair of jaws or clamps *c c*, which, as shown, are of like or similar form, except that they are reversed or made right 45 and left to fit on the opposite edges or flanges of a rail-base. They are adjustably connected and clamped upon the base of a rail by a threaded bolt *d*, passing underneath and close to the rail and through transverse holes 50 in the jaws. The jaws are preferably made of malleable iron and are formed with horizontal bearings, which fit against the bottom of the rail-base, and with longitudinal recesses to receive the edges or flanges of the

base. They are also formed with vertical 55 bearings *e e*, which are adapted to abut against one side of a tie, as shown in Figs. 2 and 3.

To insure a firm hold of the anchor upon a rail and to prevent the rail from slipping 60 therein, one or each of the two jaws is provided with one or more teeth adapted to bite into the rail-base on which it is clamped. These teeth are hardened and may be formed integrally with the jaws or separately therefrom. When they are formed integrally with the jaws, the entire jaws or the teeth alone 65 may be hardened. As shown in Figs. 2 and 4 and as preferably constructed, the jaws are provided with separately-formed hardened 70 toothed bits *ff*. These bits are fitted and inserted in the recesses of the jaws and are held in place therein before they are applied to a rail by lips *g g*, formed on the jaws at the ends of the recesses and bent over the ends of the 75 bits. Either one or both of the jaws may be provided with teeth to bite into a rail-base and with a vertical bearing to abut against a tie.

Each pair of jaws may be clamped on a 80 rail by a short bolt, or two pairs of jaws may be connected, as shown, by a long bolt or rod *d*, which serves also as a tie-rod to prevent the rails from spreading and to determine and adjust the gage of the track. When the 85 jaws are applied to the rails in independent pairs, ordinary bolts having heads at one end and threaded and provided with nuts at the other end are used. On the other hand, when they are connected in pairs, as shown 90 in Figs. 1 and 2, the long bolts or rods *d* are threaded for a distance somewhat greater than the width of the rail-base and provided with two nuts *h h* at each end. In this way the jaws of each pair are adjustably connected and clamped on the rails, and the spreading as well as the creeping of the rails is prevented. In the application of the anchors to the rails of a track in either of the ways above 95 mentioned the jaws are placed on opposite 100 sides of each rail with their bearing-faces *e* against the sides of ties toward which the rails tend to creep and are tightly clamped upon the base-flanges by turning up the nuts on the connecting-bolts, the hardened teeth 105 of the jaws being embedded in the flanges, and thus preventing the rails from slipping endwise in the anchors.

By providing bolts of different lengths or threaded for a sufficient distance to admit of it the same jaws may be readily and effectively applied to rails of different sizes or rails having bases of different widths.

With a single jaw constructed as herein shown and described a jaw of any other form and construction suitable to engage with the opposite edge or flange of a rail-base may be connected to form an effective anchor.

Various changes other than those hereinbefore noted may be made in details of construction without departing from the principle and intended scope of the invention.

This application is a division of application Serial No. 197,477, filed March 10, 1904.

I claim—

1. A rail-anchor comprising a jaw adapted to be clamped on the base-flange of a rail and having a tooth adapted to bite into the flange and prevent the rail from slipping in the anchor, substantially as described.

2. A rail-anchor comprising a recessed jaw adapted to be clamped on the base-flange of a rail and having in its recess a hardened tooth which is adapted to bite into the rail-flange and prevent the rail from slipping in the anchor, substantially as described.

3. A rail-anchor comprising a recessed jaw adapted to be clamped on the base-flange of a rail, and a hardened toothed bit inserted in the recess of the jaw and adapted to bite into the flange and prevent the rail from slipping in the anchor, substantially as described.

4. A rail-anchor comprising a toothed jaw adapted to be clamped on the base-flange of a rail, and a bearing arranged to abut against the side of a tie, substantially as described.

5. A rail-anchor composed of a pair of jaws having longitudinal recesses, hardened toothed bits in said recesses adapted to grip the base of a rail, and a bolt adjustably connecting said jaws, substantially as described.

6. A rail-anchor composed of a pair of jaws having longitudinal recesses provided with hardened toothed bits adapted to grip the

edges of a rail-base, bearing-faces adapted to abut against a tie, and a threaded bolt passing through holes in the jaws and adjustably connecting the same, substantially as described.

7. A rail-anchor comprising two pairs of jaws adapted to be clamped on the base-flanges of parallel rails, and a tie-rod connecting the two pairs of jaws, each pair of jaws having a bearing arranged to abut against the side of a cross-tie and the jaws of each pair being out of contact with each other below the rails and capable of sliding on the tie-rod, and means for holding the jaws in their adjustment on the rod, substantially as described.

8. A rail-anchor comprising two pairs of jaws adapted to be clamped on the base-flanges of parallel rails, and a tie-rod connecting the two pairs of jaws and threaded on the ends and adjustably connecting the two jaws of each pair, each pair of jaws having a bearing arranged to abut against the side of a cross-tie and the jaws of each pair being out of contact with each other below the rails and capable of sliding on the tie-rod, and a nut for drawing the jaws of each pair toward each other, substantially as described.

9. A rail-anchor composed of two pairs of jaws adapted to grip the base-flanges of two parallel railway-rails and having bearing-faces adapted to abut against a tie, and a bolt adjustably connecting both pairs of jaws and serving as a tie-rod for the rails, the jaws of each pair being out of contact with each other below the rail and capable of sliding on the rod, and means for drawing the jaws of each pair toward each other, substantially as described.

In witness whereof I hereto affix my signature in presence of two witnesses.

JOHN M. SCOTT.
